(57) **CLAIM**

I claim the ornamental design for a bracket for concealing holiday lights, as shown and described.

DESCRIPTION

FIG. 1 is a perspective view of a bracket for concealing holiday lights, showing my new design in an open position; FIG. 2 is a front elevational view thereof, illustrated in a closed position;

FIG. 3 is a rear elevational view of FIG. 3;

FIG. 4 is a front elevational view of FIG. 3;

FIG. 5 is a right-side elevational view of FIG. 3, the left-side elevational view being a mirror image thereof;

FIG. 6 is a right-side elevational view of FIG. 1, the left-side elevational view being a mirror image thereof;

FIG. 7 is a top plan view thereof; and,

FIG. 8 is a bottom plan view thereof.

The broken lines showing roof eves and a Christmas light in FIGS. 5 and 6 depict environmental matter and form no part of the claimed design. It is understood that the middle portion of the design shown in broken lines depicting indeterminate length forms no part of the claimed design.
